UNITED STATES PATENT OFFICE.

FREDERIC SMITH, OF HALIFAX, COUNTY OF YORK, ENGLAND.

WIRE-DRAWING MACHINE.

SPECIFICATION forming part of Letters Patent No. 398,982, dated March 5, 1889.

Application filed July 18, 1888. Serial No. 280,310. (No model.)

To all whom it may concern:

Be it known that I, FREDERIC SMITH, a subject of the Queen of Great Britain, residing at Halifax, in the county of York, England, 5 have invented certain new and useful Improvements in Wire-Drawing Machines, of which the following is a specification.

My improvements relate to that class of wire-drawing machines in which a single wire 10 is reduced in diameter by drawing it through a series of dies by means of a series of drawing-through pulleys driven at gradually-increasing surface speeds from the swift to the winding-on drum or wire-drawer's block, and 15 the object of my improvements is to increase the production and simplify the cost and construction of such machines.

In carrying my improvements into effect I 20 construct a machine so arranged that several wires can be drawn simultaneously, instead of only a single wire, as at present.

In order that my invention may be fully understood and readily carried into effect, I 25 will describe the accompanying sheet of drawings, reference being had to the figures and letters marked thereon.

Figure 1 is a side elevation, and Fig. 2 a plan, of a machine embodying my improvements and constructed to draw four wires 30 simultaneously through a series of six dies or holes.

In the drawings, *a* designates the draw bench or frame of the machine.

b b are two of the swifts on which the coils 35 of wire to be drawn are placed. In the machine shown, as there are four wires to be drawn, each wire would be run off from a separate swift; but to avoid reducing the drawings to a very small scale only two swifts *b* have 40 been shown.

c c' c² c³ c⁴ c⁵ are the flanged drawing-through pulleys, which are mounted, respectively, on the shafts *d d' d² d³ d⁴ d⁵*, and are driven by means of the bevel-wheels *e e' e² e³ e⁴ e⁵*, geared 45 respectively to the bevel-wheels *f f' f² f³ f⁴ f⁵*, fixed on the shaft *g*, which receives motion by means of a gear, *h*, from a gear, *i*, fixed on the main shaft *j*, which is driven by means of a belt (not shown) and a pair of fast and loose 50 pulleys, *k k'*.

It will be seen on reference to Fig. 2 that the sizes of the two series of bevel-gears *e* to

e⁵ and *f* to *f⁵* are so proportioned that the drawing-through pulleys are driven at gradually-increasing surface speeds, that of the pulley *c* being the slowest and that of the pulley *c⁵* the quickest.

Each wire is taken from its swift through a guide-eye, *m*, secured at the feed end of the draw-bench, thence through an eye or slot in 60 the front side of the first lubricating-trough, *n*, thence across the trough and through one of the first series of four dies or draw-holes, *o*, which are carried on the back side of the trough *n*, then between a guide or fork, *p*, 65 one of which is secured to the side of the trough *n* behind each die *o*, thence once or twice around the first drawing-through pulley, *c*. The drawing-through pulley, *c*, and each succeeding drawing-through pulley, is made 70 broad enough to accommodate all the four wires; but instead of having a single broad pulley it is obvious that four separate pulleys, one for each wire, might be secured upon each shaft *d*. From the first drawing-through 75 pulley *c* each wire, reduced in sectional area and correspondingly elongated by the first die *o*, passes through one of the slots in the side of the second lubricating-trough, *n'*, thence 80 through one of the second series of four dies or draw-holes, *o'*, between one of the second series of guide-forks *p'*, and around the second drawing-through pulley, *c'*, the wires having 85 been further reduced in size and elongated by the second series of dies, *o'*. In like manner the wires pass forward alternately through the series of dies *o² o³ o⁴ o⁵*, between the guide-forks *p² p³ p⁴ p⁵* and around the remaining drawing-through pulleys *c² c³ c⁴ c⁵*, the wires being further reduced in size and 90 elongated by each succeeding series of dies, and this increase in length being compensated for by the correspondingly increased surface speed of each succeeding drawing-through pulley. The function of the several series of 95 guide-forks *p* to *p⁵* is to prevent the end of any wire as a piece runs off becoming entangled with the others. The wires pass from the final series of dies, *o⁵*, over guide-pulleys *q* to the four winding-on drums or wire-drawers' blocks *r*, each of which is driven by means of a pulley, *s*, and strap *s'* from a pulley, *s²*, 100 fixed on the shaft *g*, the pulleys *s* and *s²* being so proportioned that the surface speed of

the winding-on drums r exceeds that of the last drawing-through pulley to the extent required to compensate for the elongation of the wires caused by the final series of dies, o^6 .

- 5 To insure the thorough lubrication of the several wires during the drawing process, I arrange a tank or reservoir, t , which is full of lubricating-liquor, and in which the series of drawing-through pulleys $c c' c^2 c^3 c^4 c^5$ are 45 partially immersed. The grooved flanges of these pulleys as they revolve carry up a certain quantity of the lubricant, which is collected from them by a series of tubes or channels, u , and conducted into the respective 50 troughs n' to n^6 . The first trough, n , is similarly supplied with lubricant by means of two revolving grooved pulleys, v , and a pair of tubes or channels, u' , the said pulleys v being mounted on a shaft, v' , which is driven by a 55 pulley, v^2 , and a band, v^3 , from a pulley, v^4 , fixed on the shaft d .

The several series of dies o to o^6 are placed about or below the level of the lubricant in the troughs n , so that the dies are kept cool 60 and the wires are thoroughly lubricated during their passage through the machine, and any surplus liquid escapes from the troughs n back to the reservoir t , either through the slots in the front sides of the troughs n or 65 through the dies or draw-holes o .

As an alternative arrangement for raising the lubricant from the reservoir t into the troughs n , I might employ, instead of flanges on the drawing-through pulleys, a series of 70 chains carrying cups or buckets and arranged to revolve over guides or pulleys, and to raise the lubricant from the reservoir t by means of the cups or buckets and discharge it into open channels leading to the troughs n .

75 40 What I claim as my invention, and desire to secure by Letters Patent of the United States, is—

1. In a machine for drawing two or more wires and reducing them simultaneously any required number of sizes, the combination of the swifts b , the series of revolving drawing-through pulleys c , each pulley being broad enough to accommodate on its periphery all the wires to be drawn, all the pulleys being driven by bevel-gearing at gradually-increasing surface speeds from the swifts to the winding-on drums b , which are driven at a still quicker speed by pulleys and belts, the several series of dies or draw-holes o , each series of holes being smaller than the preceding one, the lubrication of the wires being effected by immersing the revolving drawing-through pulleys in lubricant contained in a reservoir, and also by immersing the series of dies o in lubricant supplied to a series of troughs, n , all 80 substantially as herein set forth, for the purposes specified.

2. The combination, with the series of flanged drawing-through pulleys c , driven at varying surface speeds by bevel-gearing, as 85 described, and immersing in a reservoir containing lubricant, of the tubes or channels u , and the series of troughs n , substantially as and for the purposes herein described, and as shown.

3. The combination, with the series of lubricating-troughs n and the series of dies o , of the series of guides or forks p , and the drawing-through pulleys c , substantially as herein set forth, for the purposes specified.

In testimony that I claim the foregoing as my invention I have signed my name, in presence of two witnesses, this 6th day of July, 1888.

FREDERIC SMITH.
